INSTRUMENT TRANSFORMER

Robert S. Canney, Berwick, Maine, assignor to
General Electric Company

Filed Nov. 25, 1970, Ser. No. 26,151

Term of patent 14 years

Int. Cl. D13—02

U.S. Cl. 26—15

FIG. 1 is a perspective view of an instrument transformer showing my new design,

FIG. 2 is a top plan view of the instrument transformer showing my new design,

FIG. 3 is a side view thereof; and

FIG. 4 is an end view of the transformer; the other end being a mirror image thereof.

I claim:

The ornamental design for an instrument transformer, as shown and described.
